CUTTING APPARATUS

Dale M. Curtis, Nitro, W. Va., assignor to American Viscose Corporation, Wilmington, Del., a corporation of Delaware

Application May 7, 1946, Serial No. 667,869

4 Claims. (Cl. 164—38)

1

The present invention relates to apparatus for cutting continuous filamentary material into discontinuous lengths for the production of staple fiber from rayon or other synthetic filamentary material. The invention is particularly concerned with that type of fiber-cutting apparatus in which the continuous material is fed to a rotating member having a radial channel through which the material is directed outwardly, generally under the influence of centrifugal force and from which the material protrudes until cut by a cutting member which co-operates with the periphery of the rotating member. The general form of the cutting apparatus is shown in Beria Patent No. 1,723,998.

Occasionally, the fibers protruding from the rotating member are not completely severed, either because of dullness of the knife or equivalent cutting member, or because of improper co-action of the knife or filament cutting member with the rotating member. When this occurs, the fiber product will contain a certain proportion of overlength fibers which may be two or three times as long as the fiber length desired. In accordance with the present invention, overlength fibers are detected and such detection initiates the operation of means for interrupting the delivery of the cut fibers to the next succeeding stage of processing, thereby preventing the mixing of overlength fibers with the standard length fibers. The detection of overlength fibers also operates an indicator or alarm. In this fashion, the operator is advised immediately of the improper functioning of the cutting apparatus. Further objects and advantages of the invention will be apparent from the drawing and the description herein.

The drawing illustrates preferred embodiments of the invention, the electrical connections being somewhat schematically shown.

Figure 1 is a perspective view of a preferred form of the invention.

The cutting apparatus as shown in Figure 1 comprises a rotating member 2 which may be termed a rotating disc or cutting head. The rotating member 2 is provided with a radial channel 3 which communicates with the axial feeding member 4 into which the filamentary material 5 may be fed downwardly by means of a delivery roll or godet 6 (or any equivalent feeding device such as a thread-advancing device comprising a pair of canted rolls, a thread-advancing reel, or the like) about which the material 5 is lapped one or more times to provide a good grip. The delivery roll 6 is driven by a shaft 7 and conven-

2

tional driving means, not shown. A knife 8 is carried by a suitable bracket 9 fastened to a supporting frame 10, so that the protruding fiber clump 5a is cut each time the rotating member 2 carries it into contact with the knife 8. The rotating member 2 may be supported in suitable bearings upon the support 11 and may be driven by pulley 12 therebeneath.

One or more (two being shown) detecting fingers 13 are positioned radially outwardly from the periphery of the rotating member 2. Suitably, each finger 13 may be carried upon a transverse rod or shaft 14 pivotally mounted in a bracket 15 secured to the framework 10. There is also secured to the rod 14 a mercury switch 16. The pivotal assemblage of finger 13, rod 14 and switch 16 are so balanced that the finger 13 extends downwardly and is positioned just outside the normal path of the protruding fibers 5a. Since the amount by which the fiber clump 5a extends outwardly from the rotating member 2 depends upon the arcuate distance of the clump from the cutting member 8 at any particular portion of the path, the first detector finger 13 which the fiber clump 5a approaches after leaving the position of the cutting member 8 is positioned a much shorter radial distance from the periphery of the member 2 than the subsequent detector finger or fingers 13. However, each one is positioned just outside the normal path of the fiber clump, so that when the cutting apparatus is operating properly, there is no contact between the fiber clump 5a and the detector fingers 13. The mercury switches 16 are normally open when the apparatus is functioning properly. However, when overlength fibers occur in the clump 5a, such fibers strike the detector finger or fingers 13, and cause pivotal motion thereof about the axis of rod 14, thereby swinging the mercury switch and closing its contacts.

The solenoid 20 is energized whenever one of the switches 16 is closed. Energization of solenoid 20 forces the core 17 downward against the upward pressure of spring 18 which normally holds the gate or dam 19 in its upper position, the rod 18a serving to support the dam from the core. The dam 19 is perforated and operates in the guideways 30 fastened to the side walls of the trough 31 which receives the cut fibers and along which the fibers of proper length are swept to the next processing stage as by a stream of fluid, such as of water, hot or cold, discharged into the trough by the nozzle 32. A signal light 21 and a sound alarm 22 may be connected in the circuit so that the closing of switches 16 or any one of them

also sounds the alarm and turns on the light to call the operator's attention to the improper functioning of the machine. An electric supply line 23 may be connected to the electrical control system by the master switch 24 during operation of the cutting apparatus.

The electrical controlling system so far described is essentially complete in itself. However, an auxiliary detector system may be provided to indicate any decrease in tension of the material proceeding from the delivery roll 6 to cutting head 2. This detector may take the form of a feeler 25 normally pressing against the material 5 as it proceeds between roll 6 and cutter head 2 and mounted upon a shaft 26 pivotally supported within a bracket 27 and carrying a mercury switch 28 which is normally open in the position shown when the filamentary material 5 is feeding properly. When failure of the material 5 occurs because of breakage, or whenever a decrease in tension occurs for any reason, the detector system 25, 26 and 28 swings pivotally in the direction shown by the arrow, thereby closing the mercury switch 28, sounding the alarm 22 and lighting the light 21. An auxiliary stationary guide 29 may be provided in the bracket 27 to reduce fluctuation and vibration in the material 5 as it passes between the roll 6 and the cutter head 2.

While mercury switches 16 and 28 are disclosed, any other type of switch may be used. For example, the swinging of the detector systems may move a metallic contact into engagement with a stationary metallic contact in order to effect closing of the electrical control system.

The present invention provides for independent detection and signaling (1) of breakage or failure of tension in the filamentary material as it proceeds from the roll 6 to the cutter 2 and (2) of the improper functioning of the cutting member 8 resulting in overlength fibers. In the latter event, the detector system initiates operation of means for interrupting the delivery of the improperly cut fibers to the next succeeding stage of processing (thereby preventing mixing of these fibers with the properly cut fibers) and means for notifying operators.

It is to be understood that the description hereinabove is illustrative only, and that changes and variations may be made without departing from the spirit and scope of the invention as defined in the appended claims.

I claim:

1. In combination with a device for cutting continuous filaments into discontinuous lengths comprising a rotating member having a radial passage for discharging the filamentary material outwardly therefrom, a cutting member to which the rotating member presents the outwardly extending material to be cut, means for feeding continuous filamentary material to the passage in the rotating member, and means for delivering the cut fibers to a subsequent stage of handling; a movable element positioned along the path of the material on its way to the subsequent stage, means for moving the element across the path thereby detaining the cut material therealong, and means positioned a predetermined distance radially from the rotating member for detecting filament ends of excessive length extending outwardly there-

from and for initiating operation of the moving means.

2. In combination with a device for cutting continuous filaments into discontinuous lengths comprising a rotating member having a radial passage for discharging the filamentary material outwardly therefrom, a cutting member to which the rotating member presents the outwardly extending material to be cut, means for feeding continuous filamentary material to the passage in the rotating member, and a trough for delivering the cut fibers to a subsequent stage of handling; a movable dam positioned along the path of the material on its way to the subsequent stage, means for moving the dam across the path thereby detaining the cut material therealong, and means positioned a predetermined distance radially from the rotating member for detecting filament ends of excessive length extending outwardly therefrom and for initiating operation of the moving means.

3. In combination with a device for cutting continuous filaments into discontinuous lengths comprising a rotating member having a radial passage for discharging the filamentary material outwardly therefrom, a cutting member to which the rotating member presents the outwardly extending material to be cut, means for feeding continuous filamentary material to the rotating member, and means for delivering the cut fibers to a subsequent stage of handling; a movable element positioned along the path of the material on its way to the subsequent stage, electrical means for moving the element across the path thereby detaining the cut material therealong, and switch means positioned a predetermined distance radially from the rotating member for detecting filament ends of excessive length extending outwardly therefrom and for initiating operation of the electrical moving means.

4. In combination with a device for cutting continuous filaments into discontinuous lengths comprising a rotating member having a radial passage for discharging the filamentary material outwardly therefrom, a cutting member to which the rotating member presents the outwardly extending material to be cut, means for feeding continuous filamentary material to the rotating member, and a trough for delivering the cut fibers to a subsequent stage of handling, a movable dam positioned along the path of the material on its way to the subsequent stage, electrical means for moving the dam across the path thereby detaining the cut material therealong, and switch means positioned a predetermined distance radially from the rotating member for detecting filament ends of excessive length extending outwardly therefrom and for initiating operation of the electrical moving means.

DALE M. CURTIS.
